UNITED STATES PATENT OFFICE.

NATHAN OPOTOW, OF NEW YORK, N. Y.

DENTIST'S FLASK.

1,256,589.

Specification of Letters Patent. Patented Feb. 19, 1918.

Application filed December 6, 1917. Serial No. 205,816.

To all whom it may concern:

Be it known that I, NATHAN OPOTOW, a citizen of Russia, and residing at New York, in the county of Bronx and State of New York, have invented certain new and useful Improvements in Dentists' Flasks, of which the following is a specification, such as will enable those skilled in the art to which it appertains to make and use the same.

10 This invention relates to what are known as dental or dentists' flasks, and the object thereof is to provide improved means for locking the separate parts of a flask of this class together, and which may be conveniently manipulated for the purpose specified and also for the purpose of disconnecting the parts of the flask, and with this and other objects in view the invention consists in the construction, combination and arrangement 15 of parts hereinafter described and claimed.

20 The invention is fully disclosed in the following specification, of which the accompanying drawing forms a part, in which the separate parts of my improvement are 25 designated by suitable reference characters in each of the views, and in which:—

Figure 1 is a plan view of a dental flask of wellknown general form and employing my improved means for locking the parts 30 thereof together;

Fig. 2 a side view of the flask as shown in Fig. 1;

Fig. 3 a partial section on the line 3—3 of Fig. 2;

35 Fig. 4 a view similar to Fig. 3 but showing the parts in a different position;

Fig. 5 a partial section on the line 5—5 of Fig. 1;

40 Fig. 6 a view similar to Fig. 2 but showing only one part of the flask;

Fig. 7 a view similar to Fig. 6 but showing another part of the flask;

Fig. 8 a perspective view of a lock clamp which I employ; and

45 Fig. 9 a similar view of a supplemental lock.

In the accompanying drawing, I have shown at *a* a dental flask of the form now in general use, and which comprises a bottom 50 body part *b*, a top body part *c* and a cap plate *d*.

The top body part *c* is provided, in the construction shown, and in the opposite top edges thereof and in a plane which passes 55 forwardly and backwardly through the body of the flask with recesses *c*², and the cap

plate *d* is provided with lugs *d*² which enter said recesses, and on the inner side of which the cap plate is provided with triangular reinforcements *d*³, and the object of this construction is to aid in holding the cap plate in proper position on the top body part *c* and to reinforce said cap plate.

The opposite sides of the bottom part *b* of the flask is provided with angular lugs or 60 projections *b*² having upwardly directed central extensions *b*³, and the top part *c* is provided with corresponding lugs or projections *c*² having downwardly directed extensions *c*⁴ which overlap the connection of the parts *b* and *c* and are provided with recesses *c*⁵ to receive the parts *b*³.

The bottom part *b* of the flask is also provided on its opposite sides with angular lugs or projections *b*⁴, and the part *c* is provided 75 directly over the lugs or projections *b*⁴ with similar lugs or projections *c*⁶, and I also employ at the opposite sides of the flask, main clamp plates *e* provided at their upper ends with inwardly directed shoulders *e*² and near 80 their lower ends with angular apertures *e*³ through which the lugs or projections *b*⁴ pass, and above the angular apertures *e*³ the clamp plates *e* are also provided with other angular apertures *e*⁴ having upwardly and 85 downwardly directed extensions or supplemental apertures *e*⁵, and the lugs or projections *c*⁶ on the part *c* of the flask pass through the angular apertures *e*⁴ and the clamp plates *e* are movable inwardly and outwardly on 90 the lugs or projections *b*⁴ and *c*⁶.

I also provide supplemental lock devices *f* which consist of angular blocks provided at their opposite ends with lugs or projections *f*², and the supplemental lock devices *f* 95 are connected with the lugs or projections *c*⁶ by screws *g* which are passed therethrough and the heads *g*² of which are countersunk therein, and with this construction the supplemental lock devices *f* may be turned on 100 the screws *g*, and when in the transverse position shown in Fig. 2, they operate to bind the lock plates *e* in operative position as shown in Figs. 1, 2 and 3, and when said lock devices are in the position shown in Fig. 4, 105 the clamp plates *e* may be moved outwardly into the position shown in said figure, and the separate parts of the flask may be disconnected as will be readily understood.

When it is desired to again lock the separate parts of the flask together, they are placed in their normal position as shown in 110

Figs. 1, 2 and 3, and the clamp plates *e* are moved inwardly into the position shown in Fig. 3, and the supplemental lock devices *f* are turned into the position shown in Fig. 2.

5. With my improvement the separate parts of the flask when in use are securely locked against any movement, either radially, laterally or otherwise, and the use of springs or elastic connections of any kind is avoided,
- 10 and when the separate parts of the flask are properly made and fitted together, said flask when in use will be practically sealed against the passage therefrom or thereinto of either liquid or air.
- 15 The method of operating my improved flask will be fully understood by all those familiar with, or accustomed to operating devices of this class, and a detail description of such operation is, therefore, not necessary.
- 20

Having fully described my invention, what I claim as new and desire to secure by Letters Patent, is:—

1. A dental flask of the usual form and composed of a bottom body portion, a top body portion, and a cap plate, the bottom body portion and the top body portion being provided at their opposite sides with angular lugs or projections, vertically arranged clamp plates having angular apertures through which said lugs or projections are adapted to pass and on which said clamp plates are movable inwardly and outwardly, and supplemental lock devices rotatably mounted on the angular lugs or projections of the top body part and adapted to pass through the corresponding apertures in the clamp plates.

2. A dental flask of the usual form and composed of a bottom body portion, a top body portion, and a cap plate, the bottom body portion and the top body portion being provided at their opposite sides with lugs or projections, vertically arranged clamp plates having apertures through which said lugs or projections are adapted to pass and on which said clamp plates are movable inwardly and outwardly, and sup-

plemental lock devices rotatably mounted on the lugs or projections of the top body part 50 and adapted to pass through the corresponding apertures in the clamp plates.

3. A dental flask of the usual form and composed of a bottom body portion, a top body portion, and a cap plate, the bottom body portion and the top body portion being provided at their opposite sides with lugs or projections, vertically arranged clamp plates having apertures through which said lugs or projections are adapted to pass and 55 on which said clamp plates are movable inwardly and outwardly, and supplemental lock devices rotatably mounted on the lugs or projections of the top body part and adapted to pass through the corresponding 60 apertures in the clamp plates, said top and bottom portions of the flask being also provided with interlocking lugs or projections.

4. A dental flask of the usual form and composed of a bottom body portion, a top body portion, and a cap plate, the bottom body portion and the top body portion being provided at their opposite sides with lugs or projections, vertically arranged clamp plates having apertures through 75 which said lugs or projections are adapted to pass and on which said clamp plates are movable inwardly and outwardly, and supplemental lock devices rotatably mounted on the lugs or projections of the top body part 80 and adapted to pass through the corresponding apertures in the clamp plates, said top and bottom portions of the flask being also provided with interlocking lugs or projections and the cap plate and top body part 85 being provided with other interlocking parts.

In testimony that I claim the foregoing as my invention I have signed my name in presence of the subscribing witnesses this 90 4th day of December, 1917.

NATHAN OPOTOW.
